Specification for Design.

Patented Oct. 14, 1913.

Application filed July 28, 1913. Serial No. 781,665. Term of patent 14 years.

To all whom it may concern:

Be it known that I, JESSE B. GARBER, a citizen of the United States, residing at Salem, in the county of Columbiana and State of Ohio, have invented a new, original, and ornamental Design for a Pump-Body, of which the following is a specification, reference being had to the accompanying drawing, forming part thereof.

In the drawings, Figures 1 and 2 are side elevations of a pump body looking from op-

posite directions; Fig. 3 is an end view looking from the right of Fig. 1 or the left of Fig. 2.

I claim:

The ornamental design for a pump body, substantially as herein shown.

JESSE B. GARBER.
